UNITED STATES PATENT OFFICE.

CLARENCE F. COLBERT, OF HOOPESTON, ILLINOIS, ASSIGNOR TO SPRAGUE CANNING MACHINERY COMPANY, OF CHICAGO, ILLINOIS, A CORPORATION OF ILLINOIS.

CAN FEEDING AND RIGHTING MACHINE.

1,393,947.

Specification of Letters Patent. Patented Oct. 18, 1921.

Application filed January 11, 1918. Serial No. 211,432.

To all whom it may concern:

Be it known that I, CLARENCE F. COLBERT, a citizen of the United States, residing at Hoopeston, in the county of Vermilion and 5 State of Illinois, have invented new and useful Improvements in Can Feeding and Righting Machines, of which the following is a full, clear, concise, and exact description, reference being had to the accompanying 10 drawing, forming a part of this specification.

The present invention relates to can filling machines, and has to do more particularly with the mechanism by which the cans are 15 righted and delivered to their final filling positions upon the machine.

One object of the present invention is to produce a machine in which the cans will be advanced to the can carrying table in an 20 efficient and satisfactory manner. In feeding so-called "sanitary" cans, that is, cans having open tops and laterally extending seaming flanges, greater care must be exercised than in the feeding of the more rugged 25 cans having solder holes and caps. It is the purpose of the present invention to provide mechanism which will be especially efficient in feeding these "sanitary" cans and to reduce to a minimum the possibility of injury 30 to the can due to denting or mutilation of the flange, which would result in preventing the formation of a perfect seam and hermetic closure. In prior devices, where a positive feed has been employed, much injury 35 has been inflicted upon the cans because of the unyielding action of the mechanism.

Another object of my invention is to provide a simple and improved righting mechanism by which the cans may be received 40 from a gravity feed chute with their axes in a substantially horizontal position and delivered right side up with their axes in a vertical position.

In carrying out these objects I employ a friction feed for feeding the cans to the can carrying table of the machine, and for this purpose I preferably employ belts passing over pulleys. These belts coöperate with 45 fixed guides to form a feeding channel and by passing the belts over pulleys having horizontal and vertical axes at the receiving and delivering ends respectively of the channel they coöperate with the fixed guides to

readily right the cans on their way to the 55 can carrying table.

These and other objects and features of my invention will be more fully understood upon reference to the following detailed description taken in connection with the accompanying 60 drawing and the scope of the invention will be particularly pointed out in the appended claims.

In said drawing Figure 1 is a perspective view of a portion of a can filling machine 65 constructed in accordance with the present invention.

Fig. 2 is a perspective view of the same, viewed from the opposite side of the machine.

Fig. 3 is a plan view of the parts shown in Figs. 1 and 2, and

Fig. 4 is a view of the same parts in elevation.

Throughout these views like characters 75 refer to like parts.

Referring to the drawing in detail, 10 designates a portion of the main frame of the machine in which the main shaft 11 is journaled. This vertical shaft carries the 80 filling mechanism (not shown), the can carrying table 12 and a series of sweeps 13. These latter may be supported in any desired way, but are preferably secured to the filling mechanism by means of arms 14. 14. 85 A peripheral guide 15 is positioned adjacent to the periphery of the table 12 and is fixed to a bracket 16, which is in turn adjustably secured to a portion of the main frame 10. The adjustment is provided in 90 the present instance by a slot 18 in the bracket 16 through which set screws 19 are passed into threaded engagement with the main frame. By loosening up the screws the bracket 16 and guide 15 may be adjusted 95 toward and from the shaft 11 into any desired position. When once positioned the screws 19 may be screwed down tight so as to hold the parts against displacement. The forward end of the guide 15 is turned out- 100 ward in a radial direction to more readily engage the cans in their travel toward the table 12. It will be understood that in operation the filling mechanism, sweeps 13 and table 12 all move, in the direction indicated 105 by the arrow, at uniform speed.

After the cans have completed their circuit upon the table 12 they are engaged by

a delivery sweep 20, which extends into the path of travel of the cans. By this sweep 20 the filled cans are conducted from the table 12 to the auxiliary table 21 which 5 rotates in the direction indicated by the arrow shown upon it. From this table the cans may be removed in any desired way.

The main frame 10 carries an auxiliary frame 22 which is bifurcated at its outer end 10 so as to provide journal arms 23, 24. At its inner end this auxiliary frame 22 is provided with a horizontal plate 25, which extends into close proximity to the rotary table 12, and has its upper face lying substantially 15 in the same horizontal plane as the upper face of the table 12. It is to this plate 25 that the delivery sweep 20 is secured. The portion of the frame 22, adjacent to the plate 25 is provided with bearings 26, 27 for a vertical shaft 28. This shaft is driven from the main shaft 11 by means of a train of gearing, including a gear wheel 29 on the shaft 11, meshing with a pinion 30 on a counter shaft 31, and a 25 sprocket wheel 32 on shaft 31 driving a sprocket chain 33 to actuate sprocket wheel 34 upon shaft 28. The shaft 28 carries a delivery disk 35 which slightly overlaps the table 12. This same shaft also carries two 30 grooved pulleys 36 and 37, the former being positioned close to the disk 35 and the latter a short distance above it. The spacing of the pulleys 36 and 37 is of course such as to bring the belts 38 and 39, carried by them, 35 into engagement with the surface of a can. In other words the distance between the belts is somewhat less than the height of the can. The belts 38 and 39 pass over coöperating 40 grooved pulleys 40 and 41, mounted upon a horizontal spindle 42 journaled in the arms 23 and 24 of the auxiliary frame 22. The space between the pulleys 41 and 42 is such as to bring both belts into engagement with a single can as it is received from the gravity 45 chute formed by the upright strips 43, 44, 45 and 46. These strips are curved at their lower ends and secured to a rectangular frame 47, which is in turn, bolted against the upper faces of the arms 23 and 50 24. In the present instance the upper ends of the strips 43, 44, 45 and 46 are shown secured to a rectangular frame 48, which forms part of the gravity feed chute construction. It will be understood that this 55 gravity feed chute may be variously constructed, and in ordinary installations it is a chute leading from a floor above the floor on which the filling machine is located. In order to maintain the belts 38 and 39 in operative 60 engagement with the pulleys 40 and 41, guide pulleys 49 and 50 are provided upon the upper ends of arms 51 and 52 respectively. These arms are secured to the auxiliary frame 22. At the point where the 65 cans emerge from the gravity chute they en-

gage the belts 38 and 39 in a substantially horizontal plane, but as the cans proceed toward the pulleys 36 and 37 the position of the belts 38 and 39 change from a horizontal plane to a vertical plane, and consequently 70 the cans are shifted from a horizontal position to a vertical position. In order that the belts 38 and 39 may bring about this change it is necessary to provide some guiding means which will coöperate with the 75 belts. In the present instance guide rods 53, 54, 55 and 56 are provided for this purpose. Each of these rods is secured at one end to the rectangular frame 47. In each instance this is done preferably by passing 80 the rod into a socket and using a set screw 57 to hold it in place. The rod 56 is passed through an opening in plate 25 and thereby secured at its forward end. This rod as clearly shown is practically a straight rod. 85 The other rods, namely: rods 53, 54, and 55 are given a spiral twist so as to more accurately define the exact channel through which the cans pass. With this arrangement of rods it will be seen, as illustrated 90 more particularly in Fig. 1, that the rod 53 engages the tops of the cans, while the rods 54 and 55 engage the sides. The rod 54 will engage the side of the can at a point more or less directly opposite that engaged 95 by the belt 39.

Similarly rod 55 engages at a point practically opposite to that engaged by belt 38. In the righting of the can the rod 56 engages the bottom of the can. It will be 100 noted that the guide rods 54 and 55 are secured near their forward ends to a post 58 secured at its lower end to the plate 25. It will be seen from the drawings that the peripheral guide 15 has its adjacent outwardly 105 turned end located between the pulleys 36 and 37 so as to readily engage the cans as they pass the latter.

From this description of the parts it will be seen that in operation a stream of cans, 110 designated 59, will pass by gravity down through the gravity chute and be delivered, one by one upon the belts 38 and 39 at a point adjacent to pulleys 40 and 41 and each can will then be righted through the joint 115 action of the belts and the associated guides. It will be seen that if the stream of cans is stopped, the belts 38 and 39 will slip over the cans and not cause them to be injured by reason of undue pressure one upon the other, 120 or by reason of unyielding operation of any parts of the mechanism. The cans thus fed will be forced one by one against the receding can face 60 of a sweep 13, which will gradually allow the engaged can to move 125 slightly inward toward the shaft 11 as the sweep advances, until finally the can is in position to be engaged by the radial abutting face 61 of the next sweep 13. When thus engaged the can will be held by the sweep in 130

a definite position on the table 12, while the latter carries the can around to be filled and finally delivered through the action of the delivery sweep 20. In positioning the can 5 the peripheral guide 15 engages the outer portion of the can and holds it from radial displacement. It will be understood that the guide 15 will be adjusted to suit the size of the cans with which the machine is to be 10 operated. In their travel the sweeps 13 pass above the delivery sweep 20 as will be clear from inspection of Fig. 2.

It may also be pointed out that when a can is in position against the radial face 15 61 of a sweep 13 it is also in engagement with the tail of the preceding sweep 13. It will be seen that in the feeding and righting mechanism no time relation need be maintained between the parts of such mechanism 20 and the parts driven by the shaft 11. The friction drive provided by the belts of this mechanism avoid the necessity of any such time relation.

In carrying out my invention it will be 25 apparent that other friction devices than the belts 38 and 39 might equally well be employed. Other modifications of the structure herein disclosed may also be made by a person skilled in the art without departing from the scope and spirit of the invention.

What I claim as new and desire to secure by Letters Patent of the United States is:

1. A can handling machine for handling 35 sanitary cans comprising a sweep rotatable about a vertical axis, a vertical chute in which the cans are held with their axes in horizontal positions, said sweep having a receding spiral surface, against which the 40 cans are fed, and a shoulder which engages the cans after they have been fed inwardly toward the center of the sweep, along said receding spiral surface, and impositive frictional means for feeding said cans from said 45 vertical chute against said receding surface.

2. A can handling device for handling sanitary cans comprising a sweep rotatable about a vertical axis, a vertical can chute in which the cans are held with their axes in 50 horizontal position, said sweep comprising a receding spiral surface against which the cans are fed with their axes in vertical position, and a shoulder which engages the cans after they have been moved radially 55 inwardly along said receding spiral surface, and impositive frictional means for feeding the cans from said vertical chute against said receding surface, and for changing the cans from a position in which their axes 60 are horizontal to a position in which their axes are vertical, said impositive means comprising a disk rotatable about a vertical axis, on which the ends of the cans rest.

3. A can handling device for handling 65 sanitary cans, comprising a sweep rotatable

about a vertical axis, and a vertical can feeder in which the cans are held with their axes in horizontal position, said can feeder having a receding spiral surface against which the cans are fed with their axes in 70 vertical position, a shoulder which engages the cans after they have been fed radially inwardly along said receding spiral surface, and impositive frictional means for feeding said cans from said vertical chute against 75 said receding surface and for changing them from a position in which their axes are horizontal, to a position in which their axes are vertical, comprising a belt for engaging the sides of the cans. 80

4. A can handling device for handling sanitary cans, comprising a sweep rotatable about a vertical axis, and a vertical can feeder in which the cans are held with their axes in horizontal position, said can feeder having a receding spiral surface against which the cans are fed with their axes in 85 vertical position, a shoulder which engages the cans after they have been fed radially inwardly along said receding spiral surface, 90 and impositive frictional means for feeding said cans from said vertical chute against said receding surface and for changing them from a position in which their axes are horizontal, to a position in which their axes 95 are vertical, comprising a twisted belt for engaging the sides of the cans.

5. A device for handling cans comprising a sweep rotatable about a vertical axis, a vertical can chute, in which the cans are 100 held with their axes in horizontal position, said sweep having a receding spiral surface, against which the cans are fed with their axes in vertical position, a shoulder engaging the cans after they have been fed radially inwardly along said receding spiral surface, and impositive frictional means for feeding said cans from said vertical chute against said receding surface, and for changing the cans from a position in which their axes 105 are horizontal, to a position in which their axes are vertical, comprising a disk rotatable about a vertical axis on which the ends of the cans rest, a belt for engaging the sides of the cans, and a belt pulley over 110 which said belt runs, said belt pulley being coaxial with the rotatable disk.

6. A machine for handling sanitary cans comprising a sweep rotatable about a vertical axis, a vertical can chute in which the cans are held with their axes in horizontal position, and impositive frictional means for feeding said cans from said vertical chute to said sweep, and for changing the cans from a position in which their axes are horizontal to a position in which their axes are vertical, comprising a belt for engaging the sides of the cans, and a belt pulley over 125 which said belt runs located underneath the lower end of said vertical can chute. 130

7. A machine for handling sanitary cans comprising a sweep rotatable about a vertical axis, a vertical can chute in which the cans are held with their axes in horizontal position, and impositive frictional means for feeding said cans from said vertical chute to said sweep, and for changing the cans from a position in which their axes are horizontal to a position in which their axes 10 are vertical, comprising a twisted belt for engaging the sides of the cans and a belt pulley over which said belt runs located underneath the lower end of said vertical can chute.
- 15 8. A machine for handling sanitary cans, comprising a sweep rotatable about a vertical axis, a vertical chute in which the cans are held with their axes in horizontal position, and impositive frictional means for 20 feeding said cans from said vertical chute to said sweep, and for changing them from a position in which their axes are horizontal to a position in which their axes are vertical, comprising a twisted belt for engaging 25 the sides of the cans, a belt pulley over which said belt runs, having a horizontal axis and located underneath the lower end of said can chute and a second belt pulley rotatable about a vertical axis, over which 30 said belt runs.
9. A machine for handling sanitary cans, comprising a sweep rotatable about a vertical axis, a vertical chute in which the cans are held with their axes in horizontal 35 position, and impositive frictional means for feeding said cans from said vertical chute to said sweep, and for changing them from a position in which their axes are horizontal to a position in which their axes are vertical, comprising a twisted belt for engaging 40 the sides of the cans, a belt pulley over which said belt runs, having a horizontal axis and located underneath the lower end of said can chute and a second belt pulley, 45 rotatable about a vertical axis, over which said belt runs, and a disk rotatable about a vertical axis, coaxial with said second belt pulley.
10. A machine for handling sanitary cans 50 comprising a vertical chute in which the cans are held with their axes in horizontal position, and means for feeding said cans from said vertical chute and changing them from a position in which their axes are horizontal 55 to a position in which they are vertical, comprising a twisted can chute, and impositive frictional means for moving the cans along the twisted can chute.
11. A machine for handling sanitary cans
- comprising a vertical chute in which the cans 60 are held with their axes in horizontal position, and means for feeding said cans from said vertical chute and changing them from a position in which their axes are horizontal to a position in which they are vertical, comprising a twisted can chute, and impositive frictional means for moving the cans along 65 the twisted can chute, said impositive means comprising a twisted belt.
12. A can righting mechanism, comprising 70 a twisted can chute, a pulley located below and adjacent to one end of said twisted chute, and mounted to rotate about a substantially horizontal axis, a pulley located to one side of, and adjacent to the other end 75 of said twisted can chute, mounted to rotate about a substantially vertical axis, and a belt running over said pulleys, and engaging the cans for advancing them along said can chute.
13. In a can filling machine, the combination with a can carrying traveling element and means for positioning successive cans upon said element, of a gravity feed can chute along which the cans are adapted to 85 pass with their axes substantially horizontal, grooved pulleys mounted on a horizontal axis at the lower end of said chute, other grooved pulleys mounted on a vertical axis adjacent to said traveling element, belts 90 positioned in corresponding grooves in said horizontal and vertical pulleys so as to frictionally engage the cans delivered from said gravity chute in a horizontal position and frictionally advance them toward said traveling element and right them as they pass, 95 cooperating guides forming with said belts a channel for said cans, guide pulleys for said belts to assist in maintaining said belts in engagement with the grooves in said pulleys, and means for positively driving said grooved pulleys mounted on a vertical axis.
14. In a can filling machine, the combination with a can chute along which the cans are adapted to move with their axes substantially horizontal, of a can righting mechanism including fixed guides and traveling belts forming a righting channel, pulleys upon horizontal and vertical axes at the receiving and delivering ends of said channel, respectively, upon which said belts travel, and means for driving said pulleys.
